Specification for Design.

Patented June 23, 1914.

Application filed April 11, 1913. Serial No. 760,555. Term of patent 14 years.

To all whom it may concern:

Be it known that I, WALTER H. TIBBALS, a citizen of the United States, residing at the city of Syracuse, in the county of Onondaga and State of New York, have invented a new, original, and ornamental Design for a Casing for Hand Fire-Extinguishers, of which the following is a specification, reference being had to the accompanying drawing, forming part thereof.

Figure 1 is a front view and Fig. 2 a side view of a casing for hand fire extinguisher, showing my new design.

I claim:

The ornamental design for a casing for hand fire extinguisher as shown.

WALTER H. TIBBALS.
